UNITED STATES PATENT OFFICE.

EDWARD H. OVERHOLT, OF GALESBURG, ILLINOIS.

MOTOR-CYCLE HORN.

1,128,816.

Specification of Letters Patent. Patented Feb. 16, 1915.

Application filed November 11, 1913. Serial No. 800,316.

To all whom it may concern:

Be it known that I, EDWARD H. OVERHOLT, a citizen of the United States, and a resident of Galesburg, in the county of Knox and State of Illinois, have invented a new and useful Motor-Cycle Horn, of which the following is a specification.

My invention relates to that class of audible signals in which a diaphragm is caused to rapidly vibrate in order to produce an alarm.

The front frame or part of a motorcycle vibrates with relation to the rear frame or part thereof. It is as desirable that the alarm on this class of machines be mounted at the front as it is that they be so carried on automobiles. And so far as my knowledge extends, no horn having means readily and conveniently actuatable by the rider, and mounted on the front fork of a motorcycle has been devised. The problem which has confronted inventors has been to provide flexible manually operable means for causing the sound producing means to operate.

One object of the invention is, therefore, to provide flexible means whereby the sound-producing means is set in operation.

Another object is to provide novel means coöperating with a milled-edge wheel for causing an increased number of vibrations during each movement of the wheel.

It is an object to provide a cap or cover for the diaphragm and its operating mechanism which not only shields them from the elements and from dust and other foreign matter, but which is possessed of such acoustic properties as will direct the sound waves toward and out of the mouth of the horn.

It is an object to provide for adjustments of the co-acting means for causing the vibrations of the diaphragm, not only to provide for the production of sound waves of greater or lesser intensity or volume, but in order also to provide against wear.

As ordinarily constructed and mounted, horn-diaphragms are prone to crystallization at their centers—that point being the one where the flexing and reflexing movements are produced.

It is a further object to so construct one at least of the anvil securing elements which is in contact with said diaphragm that danger of crystallization is lessened, if not eliminated.

That the mechanism constituting the

means above recited be durable, strong, economic of manufacture, and efficient in operation is a prime requisite, and to provide mechanism of that character for carrying out these ends constitutes still another object.

Minor objects will be in part obvious and in part pointed out.

The invention accordingly consists in the features of construction, combinations of elements and arrangements and disposition of the parts for co-action, the scope of which will be pointed out in the claims hereof.

It will be manifest that notwithstanding I have referred to the device as a "motorcycle-horn" that term has been used primarily because of the especial adaptability to a motorcycle of the flexible cord or other similar means for operating the corrugated wheel, and that it may be used in connection with automobiles, bicycles, boats, marine-protection stations, or in fact, in any and all places where sound waves are required to travel considerable distances.

In the accompanying drawings, which illustrate two forms of alarms in which my invention may be incorporated: Figure 1 is a longitudinal sectional view, partly in elevation, the plane of section being taken in the line 1—1 in Fig. 3; Fig. 2, a similar view, the plane of section being taken in the line 2—2 in Fig. 3; Fig. 3, a rear end view, the cap removed; Fig. 4, a detail; Fig. 5, a sectional view, similar to Fig. 1, seen from the opposite direction and showing another structure for imparting flexing movements to the diaphragm, and Fig. 6, a detail.

Coming now to a detailed description of said drawings, and considering each element and part thereof, (where necessary) by a distinguishing reference numeral, uniformly employed, 2 designates a diaphragm secured between casing rings or annuli 3, 4, provided respectively with peripheral flanges 5, 6 having corresponding openings for the reception of screw-bolts 7 which are engaged by nuts 8, whereby the disk is firmly held in position.

1 indicates a resonator or horn-bell, shown as frictionally engaging an annular flange 10 on the outer end of the casing ring 4.

11 indicates an anvil or diaphragm agitator. In Figs. 1 and 2 this is shown as a

chisel-point having a stem penetrating the center of the diaphragm 2.

12 designates an angular washer seated beneath the head of the anvil, and 13 designates a similarly shaped washer (see Fig. 4) seated on the stem thereof, the disk being intermediate said washers.

14 designates a binding nut.

My object in making the washers 12 and 13 angular rather than circular (as heretofore made) and positioning them in non-registering positions is to prevent crystallization of the diaphragm—a result found with great frequency when circular washers are employed, for inasmuch as the flexing and reflexing of the diaphragm is constantly at the periphery of the washers, the continued vibrations soon tend to produce crystallization.

20 The ring 3 is provided with ears 16, 17, having apertures 18, 19, respectively. The aperture 19 provides a bearing for one end of a shaft 20 the other end of which passes loosely through the elongated aperture or slot 18 and is mounted in a bearing 21 in an L-shaped adjusting bracket 22 provided in its long arm with a slot 23, and in its short arm with an aperture for the passage of a set-screw 24 adapted to engage a nut 25 seated beneath the body portion of the ring 3.

26 designates a set-screw passed through the slot in the long arm of the bracket and through a corresponding eye in the end of 35 the ear 16, and 27 is a nut threaded on the stem thereof, whereby the bracket 22 is secured to the ear 16 after adjustments of the screw 24 to adjust said bracket and thereby similarly move the shaft 20. By thus adjusting the bracket and thereby the means for imparting impulses to the anvil and thereby to the diaphragm, the amount of flexure imparted to the latter may be regulated to cause sound-waves of greater or less 45 intensity to be set in motion, as desired, for use in cities or in the country. Fixed in any preferred manner on said shaft 20 is a wheel 28 having on its edge or periphery any suitable corrugations. Suitably secured on said shaft (or it may be to the wheel 28) is a spool 29 to which one end of a cord 32 or other flexible and windable means is secured, whereby rotary movement in one direction may be imparted to said 50 spool and thereby to the wheel 28.

30 indicates a coil spring, one end of which is secured to the ring 3 and its other end to an eye 31 secured to the wheel 28. The coils of the spring 30 are so arranged 60 that their number will be increased and the spring thereby tensioned, or energy stored therein, when the cord 32 is drawn outward or unwound from the spool, and it will be evident that when the cord is released by 65 the operator, the energy stored in said

spring will impart to the wheel, spool and shaft rotary motion in a direction contrary to that above recited. These reciprocatory rotations of the wheel 28 will cause the anvil 11 to be vibrated as it is alternately forced forward by reason of the contacts of the wheel-teeth points and as the diaphragm, which was flexed by said contacts, reflexes and returns the anvil 11 to its normal position or slightly therebeyond and into the spaces between the teeth. The combined areas of the wheel teeth which come into frictional contact with the point of the anvil 11 are very much greater than the area of the latter, which therefore wears much more rapidly. In order that its life may be doubled, I make it much greater in width than is the wheel in thickness, in order that when one side becomes worn it may be reversed and a new agitator-face presented to the wheel.

35 designates a cap or cover, a hemispherical cup in outline, adapted to fit over a portion of the casing ring 3 and preferably secured thereon by screws 36.

37 designates an eye registering with an opening in the cap 35, to which it is suitably secured.

The concavity of the cap acts in the capacity of a sounding board, and it deflects the sound waves into and through the bell or horn 1 from which they emerge with intensity.

Reference is now had to Fig. 5, in which the elements identical with or very like those illustrated in Figs. 1, 2 and 3 have been correspondingly numbered. 40 designates a vibrating arm, the threaded end of which passes through the diaphragm and is engaged by angular nuts 42 and 14. The other end of said arm engages an escapement dog or agitator 43 fulcrumed on a stud pin 44 carried by the ear 17, which in this figure is shown as somewhat extended. The wheel 28 now acts as an escapement wheel, and the two impulses imparted by the action of the alternate ends of the escapement dog will cause the diaphragm to be vibrated with extreme rapidity, whereby sound waves of great volume and intensity are produced.

The cord 32 provides an extremely flexible means for actuating the spool and from it the diaphragm. The signal (or horn being carried on the front frame of a motorcycle, and the outer end of said cord attached to any part of the rear frame, the first recited frame may be turned at will and as desired without materially affecting the mechanism. It (the cord) may be drawn from any direction, and even a quick blow against it will cause the wheel 28 to vibrate the diaphragm. When the device is used with or on any sort of vehicle, the cord may be secured to any convenient portion

thereof, and it may be sufficiently long to be operated by a person in the rear-seat or one at the side of the driver.

It has not been thought necessary or best 5 to encumber this specification and the accompanying drawing with descriptions and illustrations of additional modifications which are neither necessary to nor form any part of the invention. In fact, it is apparent without such that numerous changes 10 may be made in the details of construction and by modifications involving merely mechanical skill, without departing from the spirit and scope of the invention, viewed in 15 its broadest aspect. All this will be indicated in the claims hereof, wherein the omission of an element or the non-inclusion of reference to the detail features of the elements recited is intended to be a formal 20 declaration of the fact that the omitted elements or features are not essential to the invention covered by that claim.

Therefore, without limiting myself to particularities, except in such claims as they 25 are specifically pointed out, I claim as new and desire to secure by Letters Patent the following, to-wit:

1. Combined in a device of the class described, a rotatable shaft, a spool fixed thereon, a cord wound on the spool for imparting movement in one direction thereto, a spring encircling the shaft, for imparting contrary movement to said spool, a diaphragm, an anvil engaging it, a wheel secured on said shaft and adapted to impart vibratory movement to said anvil, and means for adjusting one end of said shaft toward or from said diaphragm.

2. Combined in a device of the class described, a rotatable shaft, a spool fixed thereon, a cord wound on the spool for imparting movement in one direction thereto, a spring

encircling the shaft, for imparting contrary movement to said spool, a diaphragm, an anvil engaging it, a wheel secured on said shaft and adapted to impart movements to said anvil, a shell having an ear in which one end of the shaft is mounted, and means for adjusting the other end of said shaft toward or from said diaphragm.

45

50

55

3. In a device of the character described, an annular casing-ring, a diaphragm the edge of which is secured thereto, an anvil removably secured to said diaphragm, a cord-actuated wheel having a milled periphery adapted for engagement with said anvil, a shaft on which said wheel is secured, and means for adjusting one end of said shaft relatively to said diaphragm.

4. In a device of the character described, 60 an annular casing ring, a diaphragm the edge of which is secured thereto, an anvil arranged at the center of said diaphragm, a shaft, a wheel secured on said shaft and adapted to actuate said anvil, a spool secured on said shaft, a spring coiled on said shaft, one of its ends engaged with a fixed portion of the horn and its other end with said spool, a cord wound on said spool and adapted to store 65 energy in said spring, whereby when the cord is released said spring will impart reverse movement to said spool and thereby to said wheel, and means for adjusting one end of said shaft relatively to said dia- 70 phragm.

In witness whereof, I hereto affix my signature, at Galesburg, Illinois, this 8th day of November, 1918, in presence of two subscribing witnesses.

EDWARD H. OVERHOLT.
